UNITED STATES PATENT OFFICE.

GEORGE F. PARKER AND HAROLD E. NOCK, OF NEWBURYPORT, MASSACHUSETTS, AS-SIGNORS TO TOWLE MANUFACTURING COMPANY, OF NEWBURYPORT, MASSACHUSETTS, A CORPORATION OF MASSACHUSETTS.

DESIGN FOR A PLATE OR ANALOGOUS ARTICLE.

Application filed March 24, 1924. Serial No. 9,047. Term of patent 3½ years.

To all whom it may concern:

Be it known that we, GEORGE F. PARKER and HAROLD E. Nock, citizens of the United States, residing at Newburyport, in the county of Essex and State of Massachusetts, have invented a new, original, and ornamental Design for a Plate or Analogous Article, of which the following is a specification, reference being had to the accompanying drawing, forming a part thereof.

The figure is a plan view of a plate showing our new design.

The dominant feature of the design is the

marginal ornamentation, a section only of which is shown in the drawing.

It will be understood that the complete marginal ornamentation is formed by repeating the illustrated section throughout the circumference of the plate.

We claim:

The ornamental design for a plate or analogous article, substantially as shown and described.

GEORGE F. PARKER.
HAROLD E. NOCK.
